UNITED STATES PATENT OFFICE.

FREDERICK EUGENE PERNOT, OF WASHINGTON, DISTRICT OF COLUMBIA.

ELECTRIC TELEGRAPH APPARATUS.

Application filed October 27, 1923, Serial No. 671,136, and in Great Britain October 28, 1922.

The present invention has reference to methods and means for maintaining synchronous operation of apparatus located at different positions in a telegraph system or in general between electric impulses and a mechanical motion, and has particular although not exclusive application to submarine telegraph systems.

The principal object of the present invention is to insure that any or all of the apparatus concerned in the handling of telegraph messages at the two ends of a system for transmission are driven at equal speeds and are maintained in substantially constant relative phase position. Speed, in the sense used here does not necessarily mean rotational speed, but may include frequency of reciprocation for reciprocating parts, or in general, the frequency of recurrence of recurrent operations.

The principal feature of the present invention is the utilization of current impulses such as are constituted by signals to compel and preserve the synchronous operation of apparatus.

Another feature of the invention consists in providing mechanism which synchronizes with phenomena recurrent at integral multiples or aliquot parts of the period of the elemental impulses.

A further feature of the invention consists in utilizing current changes incidental to the signals for effecting speed control.

A subsidiary feature of the invention is the utilization of the end or ends of signals in the process of speed control.

Still another feature of the invention consists in the provision of means for producing electric impulses corresponding to the beginning and/or ending of each signal.

A further feature consequent upon the last preceding feature consists in suppressing impulses in one direction so that only impulses corresponding to one end of each signal are retained.

A still further feature of the invention comprises the provision of means whereby the speed corrective effort of the impulses is applied in such a direction as to reduce any accumulated phase deviation.

Yet another feature of the invention is found in the provision of means whereby through the medium of the speed controlled

apparatus the received signals are re-translated for re-transmission or other purposes. 55

A still further feature of the invention consists in the transmission of current variations when signals are not being sent over the line for the purpose of maintaining the speed control.

A further feature of the invention is to be found in the means whereby either Morse or "cable" code signals are made effective in exerting the desired control.

Further features of the invention will be 65 more fully appreciated from the following description and appended claims, and in order that the invention and its mode of operation may be completely understood, reference will now be made to the accompanying diagrammatic drawings wherein:—

Fig. 1 represents one embodiment of the invention.

Fig. 2 represents the electrical conditions as functions of time in different portions of 75 the system for single or double current Morse signals.

Fig. 3 is adapted to illustrate the connection of a system according to this invention in a cable transmission system. 80

Fig. 4 represents the electrical conditions as functions of time in different portions of a cable transmission system in accordance with this invention utilizing double current Morse signals.

Fig. 5 illustrates a method of securing impulses corresponding only to one end of each signal.

Fig. 6 is a modification and

Fig. 7 is adapted to illustrate a complete 90 system in accordance with this invention.

One embodiment of the present invention is shown in Figure 1 wherein an electric motor M is made to run in synchronism with the unit signal impulses of the Morse code, 95 and wherein the method is as follows: At A in Figure 1 are the terminals at which powerful substantially square topped Morse electric current signals are available (as at receiving station). In addition to apparatus 100 concerned with the reception and utilization of the signals (not shown in the figure), there is connected to the terminals A the primary winding T_1 of a transformer or coupled circuit. A condenser C_1 and resistance R_1 are associated with the primary

winding of the transformer for reasons to be given later. The secondary winding T_2 of the transformer (or coupled circuit) with its associated condenser C_2 is connected to the filament F and grid G of a three-electrode thermionic valve. A steady source e is put in the grid circuit to maintain the grid potential normally at such a value that the plate or anode current is just at the point of becoming appreciable. The plate circuit of the valve contains a battery B and goes from the anode P and filament F by way of leads g_1 and g_2 to a continuously operated reversing switch or equivalent device S . The reversing switch S may be of any one of several well known types, and is operated synchronously with and by the motor M whose speed is to be controlled. The circuit leaving the reversing switch passes by leads h_1 and h_2 through resistance R_3 to an auxiliary field winding F_2 of the motor M . A condenser C_3 is connected in shunt with the auxiliary field winding F_2 . The motor M is shown in this case as a shunt motor with normal field winding F_1 and power supply E .

To describe the manner of working of the system shown in Figure 1 reference is made to Figure 2 wherein are depicted the electrical conditions as functions of time in different portions of the system. Curve a , shows square topped Morse signals representing the letter "F". The zero line is not shown because the operation of the system shown in Figure 1 is independent of the datum of current about which the signals are formed, so that a , may represent either single or double current Morse signals. The signals are characterized by sudden changes indicated at 1, 2, 3, 4, etc. in Figure 2, curve a of E. M. F. at the terminals A of Figure 1. These sudden changes act upon the primary T_1 of the transformer and produce current variations therein which in turn cause in the secondary T_2 transient voltage impulses. These transient voltage impulses shown as curve b , in Figure 2 are impressed upon the valve grid G in Figure 1. The shapes of the transient currents and voltage impulses are controlled by the resistance R_1 and condensers C_1 and C_2 in a manner well known in the theory of coupled electric circuits, and it is desirable so to adjust these circuit elements as to produce in the curve b , substantially symmetrical voltage impulses.

Curve c , in Figure 2 shows the current resulting in the anode or plate circuit g_1 and g_2 of the valve. The positive impulses 1', 3', etc. on the grid resulting from the sudden rises 1, 3 etc. in the signal E. M. F. reproduce themselves in the plate current as at 1', 3', etc., but the negative impulses 2', 4', 6', etc., resulting from the sudden drops 2, 4, 6 etc. in the signal E. M. F. do not appear in any way in the plate circuit of the valve, be-

cause of the well known uni-lateral characteristics of the valve. Thus, there are produced in the plate output circuit g_1 and g_2 unidirectional impulses corresponding to the sudden rises only in the signal E. M. F. It is the function of the transformer and valve to produce these impulses, and it is the function of the remainder of the apparatus shown in Figure 1 so to utilize these impulses as to compel the motor M to run synchronously with phenomena recurrent at integral multiples of the period of the elemental signal; that is, the motor M synchronizes with the signal fronts 1, 3, 5, etc. of dots and dashes because from the nature of the code the time interval between any consecutive current rises is an integral multiple of the time interval between consecutive current rises when only dots are being sent.

The plate circuit current c , in Figure 2 is taken to the auxiliary field winding F_2 in Figure 1 through a reversing switch S which is operated continuously by the motor M at approximately (exactly so after the synchronizing action of the invention being described is brought into play) the frequency of the signal dots; that is, two reversals take place within the time duration of a dot. The current supply to the auxiliary field winding F_2 depends in direction upon the position occupied by the switch S . Let us now suppose that conditions for the motor M are such that it is running exactly in synchronism with arriving dots, and that the phase of switch operation is such that the reversals take place exactly at the center of the plate circuit current impulses c , then the impulse impressed upon the auxiliary field winding F_2 will be as shown in curve d , Figure 2, and consists of equal positive and negative half impulses. The resultant average field excitation is unchanged and the motor therefore continues to run at the same speed and in the same phase (measured by the relation of switch reversal to arriving signal front) as though the auxiliary field F_2 were not present.

Now suppose that from some cause the load on the motor is lightened so that its speed increases slightly. The phase of switch operation will then be advanced with reference to the impulses c , in the plate circuit, so that instead of equal and opposite half impulses as shown in curve d , being impressed upon the auxiliary field F_2 , there will be impressed impulses of the type shown by curve e , of Figure 2. These impulses are of a one-sided character, and because of the preponderance of current in one direction the resultant field of the motor is altered and its speed thereby affected. By a proper choice of the direction of connecting to the field winding F_2 this alteration in average field excitation can be made to cause the motor to run more slowly, thereby neutralizing the origi-

nal tendency towards higher speed. Having established the proper direction of connection, then slow running of the motor will cause a slight lag in phase of switch operation and this in turn results in an alteration of the average excitation in such a direction as to cause the motor to run faster and thus restore the original proper speed.

It will be noticed that the synchronizing systems herein described possess in common with all other synchronizing systems this feature, namely, that a slight alteration in phase is required to bring into operation those forces which prevent an indefinite increase in phase deviation.

It will be obvious that the above method as so far described in its application to Morse code signalling can equally well be employed in connection with the well known Baudot system of signalling, or with any other system of signalling in which the E. M. F. and current changes occur at times which, in principle, are precise and definite, and which are separated by definite integral multiples of a time element which is a simple function of the speed of signalling. This general adaptability is partially illustrated in Figures 3 and 4. In Figure 3 is shown a cable system comprising a cable O, earth 4, double-current Morse transmitting apparatus X at the end 1 of the cable and a receiving relay 3 at the end 2 of the cable. From the receiving relay 3 go leads 5 to apparatus concerned with the reception and utilization of the signals, and also from the receiving relay go leads 6, connected either in series with or, as shown, in parallel with the leads 5, to connect to and operate a polarized relay 7. All of the devices indicated in the figure are well known in the art. The output terminals of the polarized relay 7 are at A and to these terminals and including a battery, the apparatus as shown in Figure 1 are to be connected.

In Figure 4 the curve α shows the double-current Morse signals delivered to the end 1 of the cable O in Figure 3. The curve r , in Figure 4 shows the signals substantially as received and as delivered by the receiving relay 3 at the end 2 of the cable. Because of the great attenuation along the cable the dots do not appear individually in the curve r , but only make themselves apparent by a zero average current. If, now, the polarized relay 7 in Figure 3 be adjusted in a well known manner to have a marking bias, then its contact tongue will remain on the spacing side only so long as a negative or spacing current flows through the relay winding. When the relay current becomes zero or positive as for a marking current, then the relay tongue will move over to the marking side under the action of the bias, assisted if it so happens by the marking current in the winding, and the result, therefore, of the sig-

nals as shown by curve r , applied to the relay winding is to produce an output from the relay as shown by the curve α , in Figure 4. The changes 1, 3, and 5 from negative to positive in curve α , representing the output from the relay occur substantially coincidently with the changes 1°, 3°, and 5° from spacing current in the signal curve r , of Figure 4. Furthermore, the changes 1, 3, and 5 of curve α , occur at instants corresponding to the beginnings of signal elements in curve α . It will be observed that the positive current in curve α , lasts throughout the duration of a letter, so that, in fact, the arrangement just described in connection with Figure 3 works only upon the beginnings and endings of letter spaces, word spaces, or similar periods of considerable duration wherein spacing current is sent to line at the transmitting end of the cable, for it is only during such spacing current intervals that a negative or spacing current affects the relay 7 in Figure 3. If, now the terminals A in Figure 3 are made to constitute the terminals A in Figure 1 and a battery is included (as presupposed) within the output circuit of relay 7 in Figure 3, then the apparatus shown in Figure 1 will function as previously described, utilizing the impulses 1', 3', and 5' of the curve b , in Figure 4, which curve corresponds in its case to curve b of Figure 2, and represents the impulses derived from the secondary of the transformer T_1 and T_2 of Figure 1 consequent upon the signals represented by curve a of Figure 4 impressed upon the primary winding.

It is obvious that the point of and manner of action in the production of transient impulses can be altered by changing the bias or polarization of the relay 7 in Figure 3, and any of the several possible modifications based upon such changes can be utilized equally well in effecting the purposes of the present invention.

In cases such as that described in regard to Morse code signals, it is characteristic of such signals that all changes of current incident to the beginnings (or endings) of signal elements are in the same direction and spaced in time by integral multiples of a fundamental time period. In the case of cable code signals the two conditions above are not fulfilled. The beginnings (or endings) of all signal elements are spaced in time by integral multiples of a fundamental time period, but these changes may be in either direction. As a consequence, therefore, the system as described in connection with Figure 1 is not applicable directly when supplied with cable code signals. It can readily be made operable, however, by inserting ahead of it a non-polarized or equivalent relay which acts to change the cable code signals into signals all in the same di-

rection. A centre-zero polarized relay with the two contacts joined together serves to do this as well as a non-polarized relay.

The system shown in Figure 1 comprises several distinct parts each of which performs a characteristic type of function, all, however, working towards the control of the speed of the motor M.

1. The transformer or coupled circuit T_1 and T_2 produces electric impulses corresponding to the beginnings and endings of signals; that is, at those places within the signals most definitely located in relation to time, where their time-derivative is a maximum.

2. The thermo-ionic valve whose function is to shut out those impulses in a negative direction and thus retain only impulses corresponding to one end of a single impulse.

3. A reversing switch rigidly operated by the motor or other mechanism whose speed is to be controlled and whose function is to apply the speed-corrective effort of the impulses in such a direction as to reduce any accumulated phase deviation.

It is obvious that the three several functions above may be performed in diverse ways by many kinds of mechanisms, all of which result in the same thing, namely, the maintenance of substantial synchronism between local apparatus and incoming signals.

The third function above is best performed in a manner described by myself and another in British patent specification 196,971, whereby a corrective effort consequent upon a deviation of phase is made first to correct the phase deviation by removal and then gradually and to an extent dependent upon the integral of all phase corrections to alter the speed so as to require less frequent phase correction.

In regard to the first function above an impulse of current corresponding to the beginning (or ending) of a signal can be secured in several ways as for instance, as shown in Figure 5 by means of a condenser and relay operated by the signals. In Figure 5 at A are shown terminals at which signals are available; for example assume signals of the type given by curve r , in Figure 4. The winding 8 of a polarized relay is connected to these terminals, and the tongue 9 of the relay plays between the two contacts 10 and 11 to which is connected a battery 12. The relay is adjusted to have marking bias so that the tongue 9 makes contact with the mark contact 10 unless a negative or spacing current flows in the winding 8. Lead 14 from the tongue 9 contains a series condenser 15, and another lead 13 is taken from the mid point of the battery 12. At the terminals B of leads 14 and 13 there will appear transient impulses exactly like the impulses shown in curve b , of Figure 4 when the received signals at terminals A are like

those of curve r in Figure 4. These impulses at terminals B are also of the same type as those shown by curve b , of Figure 2, and hence may be utilized in the manner de-

scribed in connection with Figure 1 wherein a thermo-ionic valve is used to produce a uni-lateral effect or, alternatively the uni-lateral effect may be secured through the use of a polarized relay as further to be de-

scribed in connection with Figure 5. In Figure 5 the terminals B of leads 14 and 13 are connected to the winding 16 of a polarized relay whose function is to replace the valve of Figure 1. The relay tongue 17 is

adjusted with a slight spacing bias to cause it to rest normally upon blank contact 19. A positive current in the winding 16 causes the tongue 17 to make contact with contact 18 and thus by means of lead 20 and 21 and battery 22 energizes the circuit as shown

terminating at terminals C. The impulses delivered to terminals C are thus all in one direction and consequent upon only the positive impulses present at terminals B. Hence the impulses at terminals C are identical

with those shown by curve c in Figure 2 and can be used subsequently as described in connection with Figure 1 or in any alternative methods. The net result of the arrangement shown in Figure 5 is to deliver at terminals C one-way impulses corresponding to the terminations of the letter spaces in received signals of the kind shown by curve r in Figure 4, which are those normally con-

sequent upon double current Morse working over a submarine cable at a speed sufficient to result in the suppression of dots as mentioned.

As indicated in Figure 1 the speed corrective effort is derived through the action of the impulses directly upon the motor

through the auxiliary field winding as described. These corrective efforts are only momentary but a continuity of application

can be secured by causing the corrective impulse to actuate first a lazy-tong relay and then to secure the speed corrective effort through the contacts controlled by this relay. Such a method permits of the control

of much stronger forces or greater power than can be secured from the impulses themselves.

Figure 6 shows an alternative method of producing one-way impulses in a circuit to correspond to either the beginnings or ends

of signals. At A are terminals from which are delivered signals of, for example, the type shown in curve r , of Figure 4, and to these terminals is connected the winding 23

of a polarized relay. The relay is given a marking bias so that the tongue 24 makes contact at 26 except when a spacing current flows in its winding 23, in which case it is held against the idle back contact 25.

Therefore, in the reception of signals like

100

105

110

115

120

125

130

135

140

those indicated by curve *r* in Figure 4 the tongue makes contact with 26 during the whole of every letter or equivalent. Lead 28 containing a battery 27 makes connection with contact 26 and passes through a relay tongue 30 and back to contact 32 thereof and thence by way of lead 33 to one of the terminals C. The other terminal C is joined by leads 34 and 29 to the polarized relay tongue 24. When relay tongue 24 closes on contact 26 an electric impulse is delivered to terminals C through the circuit just described, including the auxiliary relay contact 30 to 32. The relay tongue 30 is controlled by a magnet 31 around which is connected a condenser 36. The magnet 31 and its condenser shunt 36 are connected through resistance 35 to leads 28 and 29. Upon closing of the contacts 24 and 26 the magnet 31 is energized, but because of the resistance 35 and condenser 36 it becomes magnetized slowly in accordance with well known principles so that a definite and determinable (depending on condenser 36 and resistance 35 as well as upon the self inductance of the winding 31) length of time elapses between the closing of contacts 24 and 26 and the opening of the contacts 30 and 32. Thus it is only during this period of time that the terminals C are energized consequent upon the closing of contacts 24 and 26. When these contacts open consequent upon the re-establishment of spacing current in the relay winding 23 no impulse appears at terminals C. The device shown, therefore, performs both functions 1 and 2 listed above, and delivers at terminals C impulses of the type shown at *c* in Figure 2, that is, in one direction only and at only the beginning of a signal. Following after the terminals C may be connected the reversing switch, etc., of Figure 1 for the purpose of utilizing the impulses in the maintenance of synchronism as described. The method just described in connection with Figure 6 offers a considerable advantage in the fact that the impulses are obtained directly from the closing of contacts in a battery circuit and do not depend upon the discharge of energy from an energy-storing field such as a condenser, or upon transients produced by inductively coupled circuits. The advantage is a practical one concerned in the behaviour of contacts under the action of interrupted currents.

A great advantage attaching to the use of synchronous apparatus at the ends of a telegraph cable system is that the dots, which because of great attenuation along the cable do not appear individually, can be produced locally at the receiving end at exactly the proper rate and in the proper position relative to the dashes. In general, the use of synchronism makes possible the reformation of incoming signals and the retransmission

of perfectly formed signals. In submarine cable telegraphy, great difficulty attaches to the direct relaying of signals out of one cable and into another, because shaping errors are thus propagated and magnified. The use of an apparatus which receives slightly imperfect signals and sends on perfectly formed signals permits the working of any number of cables in sequence and thereby the use of shorter lengths of cables in the several sections in order to gain in speed of signalling.

Figure 7 shows a complete system incorporating a synchronizing system similar to those previously described for the reception reformation, and the re-transmission of signals from one cable into another. The apparatus is shown (for the sake of simplicity) as connected to a non-duplexed cable, but the method of application to a pair of duplexed cables by the use of two of such systems is obvious.

In Figure 7 a cable 37 has transmitted to it by transmitter 39 connected to earth 38 cable code signals. At the receiving end 41 of the cable the signals after passing through the inductances and condensers ordinarily used to help in shaping (but not shown in the figure) are taken to the receiving relay coil 42 and thence to earth 40. As is common in practice, the antenna 43 of the coil 42 plays between the butts 44 and 45 making a contact with 44 (for example) for dots or positive current, and with 45 for dashes or negative current. The two halves 46 and 47 of a battery are connected between the butts 44 and 45. The antenna 43 is connected by lead 49 to the winding 51 of a centre-zero relay (whose use will be described later) and thence by way of lead 50 to the winding 52 of another centre-zero relay and thence by way of lead 48 to the middle of the battery 46 and 47.

The relay winding 52 constitutes the beginning of the synchronizing apparatus. It carries currents delivered by the antenna 43 through its butt contacts; that is, the signal current which ordinarily constitutes "block" signals. The tongue 53 of the relay whose winding is 52 plays between the contacts 54 and 55 but since contacts 54 and 55 are joined together as shown the current produced by battery 57 in the circuit through tongue 53 and either contact 54 or 55 is always in the same direction through the apparatus 57 fed by the circuit just named. The relay 52 and 53 therefore, performs the necessary operation of rectifying the reversed current impulses of cable code signals.

The apparatus 57 supplied with rectified signals as described above consists of the system shown in Figure 6 or equivalent thereto, and whose function is to produce momentary one-way impulses at the beginnings of signal elements as described in connection

with Figure 6. The output leads 58 and 59 from apparatus 57 (corresponding to leads from terminals C in Figure 6) go to a commutating or, as shown in Figure 7, a reversing device consisting of two half segments of a slip ring 60 upon which bear brushes 61 and 62. The slip ring 60 is mounted on or driven by the shaft 64 whose speed is to be controlled. It is the function of the slip ring and brushes to control the direction of the current impulse from apparatus 57 so as to cause it to actuate further apparatus in the proper direction to correct any error in phase position of the rotating shaft 64 with reference to incoming signals. It is desirable to arrange the brushes 61 and 62 in a suitable manner to permit rotation by hand about the axis so that the datum point about which phase correction takes place can be selected at will.

The shaft 64 is driven through differential gearing comprising master gears 65 and 67 with two idler pinions 68 and 68' mounted within a ring (or equivalently) 69, the outer periphery of which is cut to form a gear. When the idler ring is held stationary then the shaft 64 is driven by gear 65 at the same speed as gear 67 which, in turn, is driven by the motor 66 through shaft 64'. The phase of shaft 64 can be advanced or retarded by rotating the idler ring 69, and this advance or retardation of phase is what is controlled by the electric impulses delivered through brushes 61 and 62 to the winding 63 of a centre-zero polarized relay. The direction of impulse current in the winding 63 depends upon the position beneath the brushes 61 and 62 of the segmental slip ring 60. For one, say positive, direction of current the relay tongue 80 is deflected upwards against contact 79. Current then flows from battery 82 through contact 80 and 79, magnet winding 78, and lead 83. This energizes magnet 78 and draws down the armature 75 against the force of the restraining spring 76. Pawl 74 guided by studs 77 engages the ratchet wheel 72 and turns it a little. This acts through shaft 71 and gear 70 upon the idler ring 69, thus slightly altering the phase of shaft 64 and whatever members are attached thereto or operated thereby. By a proper choice of direction of connection and position of brushes 61 and 62 this movement can be made to constitute a correction to an error in phase position. No correction takes place when the impulse delivered from the apparatus 57 consequent upon the beginning of a signal occurs at that instant when brushes 61 and 62 rest upon the insulation between the segments of the slip ring 60. Magnet 78', its armature 75', pawl 74', guide studs 77', and restraining spring 76' connected by leads 79' and 83' to the battery 82 and relay tongue 80 act upon ratchet wheel 73 also attached to shaft 71 in a manner identical with that of

the corresponding elements 78, 75, 74, 77 and 76 just described to rotate the shaft 71 and gear 70 in the opposite direction consequent upon a negative current through relay winding 63, in which case the tongue 80 makes contact at 79'. A reverse correction is thus obtained for a reversal of impulse current in brushes 61 and 62.

If the motor 66 runs almost exactly at a speed corresponding to the frequency of arriving signals, then only an occasional correction to phase as described above will be required. It is desirable to reduce to a minimum the number of phase corrections, and mechanisms are provided to alter the speed of the motor in a manner dependent upon the integral of all phase corrections so as to keep its speed sensibly equal to that required by the arriving signals.

The motor 66 as shown is a motor which runs synchronously with respect to impulses in the current driving it. Such a motor is well known in the art under various names, chief of which is "phonic wheel". The current impulses for driving it are conveniently obtained through contacts operated by a vibrating reed or tuning fork, maintained in continuous vibration by auxiliary contacts and a magnet similar to ordinary electric alarms or buzzers. A reed of this type is shown at 91 rigidly supported at 97. A weight 92 on the reed serves to adjust roughly its frequency. Contact 93, magnet 94, and battery 95 serve to maintain the reed in vibration. Current from battery 102 flows through lead 96 and the reed, and thence alternately through contacts 98 and 99 through leads 100 and 101 to the two windings 104 and 105 of the motor. Common return to the battery is by lead 103. The motor and reed now run in synchronism and as a result of the reed characteristics the speed is maintained very steady. A spring 90 is attached to the end of the reed 91 and is constrained at some point along its length by the two pins 89 mounted in a sliding block 87. This block moves along a slide formed by members 88 under the action of a lead screw 86 which in turn is actuated by shaft 71 through gears 84 and 85. When pins 89 are near to the reed 91 then the stiffness of the spring 90 is increased and the frequency of reed vibration is increased, and vice versa. With the gears 84 and 85 and the lead screw 86 as described, the frequency of reed vibration is thus gradually affected by the accumulation of phase corrections brought about through shaft 71 and ratchets 72 and 73, and by a suitable choice of direction of thread on lead screw 86 or of the gear connections the change in vibration frequency of the reed (and hence of motor speed) can be made such as to require less frequent phase corrections.

The shaft 64, as the result of the processes

described above is driven substantially in synchronism with arriving signals and can be utilized, therefore, to drive mechanisms adapted to retransmit perfectly formed signals corresponding to the more or less distorted block signals as received. The received block signals pass through relay winding 51. The relay tongue 106 is controlled so as normally to stand between the two contacts 107 and 108. A dot or a block representing a series of dots causes contact at 107 and a dash or a series of dashes cause contact at 108. Contact at 107 causes current from the battery 109 to flow through leads 112 and 113, through magnet 114, and this draws down armature 116. A cam 130 is driven by shaft 64 and bearing against it is a cam follower 118. A movable selector piece 117 is held against the cam follower 118 in such a manner that the movement of the armature 116 under the action of the magnet 114 causes it to engage with a key 122 carrying contacts 123. The motion of the follower 118 derived from the cam configuration is thus transmitted through the selector piece 117 to the key 122 and this latter carrying contacts 123 causes contact to be made first at 124 and then at 125 depending upon the position of the cam 130. Contact is thus made alternately at 124 and 125 as long as current in magnet 114 holds down the armature 116. The key 122 in reality constitutes one lever of an ordinary cable code transmitting key, the other lever of which is key 126. Therefore, when contacts 127 of key 126 are closed against contact 129 the continued operation of key 122 as described results in the production of a continuous series of dots or positive currents impressed by battery 132 through leads 134 and 133 to a cable or line 136 and earth 135. This series of dots lasts as long as the current continues in magnet 114, and therefore a series of dots received by receiving relay 42 and 43 as a block signal is re-transmitted by the devices described as a perfect series of individual dots. In a similar fashion, the reception of a dash or series of dashes represented by a negative current causes relay tongue 106 to make contact at 108, and thus to energize magnet 115 through leads 110 and 111 by battery 109. Armature 119 and selector piece 120 are thus drawn down into position to cause the motion of the cam 131 to be transmitted through follower 121 and selector piece 120 to key 126. Successive contacts at 128 and 129 are, therefore, made by contact 127 on key 126, resulting in a series of dashes or negative currents being delivered to the cable 136 and earth 135.

The function of the apparatus shown in Figure 7 is now completed; perfect mechanically formed signals are transmitted to the new cable 136 consequent upon slightly imperfect received signals from cable 37 and

the attainment of this is rendered possible by the synchronous motion of the shaft 64, maintained as described.

It is obvious that the method described above in connection with Figure 7 for the retransmission of cable code signals is equally adapted to the re-transmission of Morse code signals or Baudot signals, or the signals representing any other telegraph code, provided that they possess the necessary qualification of beginning or ending at definite times separated by an integral multiple of a fundamental time period. Certain modifications well known in the art will, of course, be required in the relays leading up to and in the mechanisms of the device effecting the re-transmission of the signals, but the actual arrangement of this device does not constitute a part of the present invention.

A great variety of mechanism may be employed for effecting the motion of the phase correcting device, for example a reversing clutch controlling the motion delivered by a continuously rotating shaft, or the differential gearing as shown may be omitted and the phase of the motor driving the controlled shaft be controlled by a control exercised upon the phase of the impulses driving it. In such a case as this latter, the impulses would be obtained from adjustable cam-operated contacts driven by an auxiliary motor driven from the vibrating reed. Alternatively, in those cases where great refinement in phase control is not required, the phase adjustment may be dispensed with and the speed control exerted directly upon the vibrating reed or whatever controls the speed of the prime mover, as illustrated in connection with Figure 1 for a shunt motor.

In place of the slip ring shown in Figure 7, cam or otherwise operated contacts can be used to produce the same result, and this result can be either in the nature of a current reversal as described, or it can be a commutation of current to two apparatus, each operating to effect correction in one direction.

The speed and phase-controlled shaft (as at 64 in Figure 7) need not be used directly to operate further mechanisms. It may drive cam operated contacts from which any number of impulse motors (phonic wheels) may be driven, in which event all of the motors so driven will be maintained in phase and synchronism with the arriving signals, and such motors may then be used in the further handling or re-transmission of the received signals, or for any purpose desired.

It is obvious, from the nature of the systems described, that signals of some sort are required to maintain synchronism at the two ends of the cable or line, and for this reason it is proposed to equip the transmitter with an attachment providing for the transmission of continuously repeated

signal elements of a suitable type for the purpose of maintaining synchronism during those intervals when no messages are being transmitted. Methods for doing this 5 do not constitute part of the present invention, but one such method consists in providing an endless band or tape perforated to represent the desired signal elements, and to be run through the transmitter repeatedly 10 during idle periods. It will be appreciated that one of the advantages attaching to the use of the present system is that no time is consumed during the transmission of messages, as has been done heretofore, in sending 15 over the line currents or impulses expressly designed to maintain synchronism.

It is obvious that the methods described do not depend in principle upon the transmission of the controlling signals over a long 20 cable or other circuit. The methods are applicable to the maintenance of synchronism generally, between a mechanical motion and electrical impulses separated by a definite time interval or integral multiples of that 25 interval, and numerous useful applications of this kind exist.

I claim:

1. A system of the type described comprising means to generate and transmit signal 30 impulses at intervals, and of duration, which are integral multiples of the period of the elemental impulses, a receiving station having a distributing device for said signal impulses and means to drive said distributing 35 device, with means responsive to the said signal impulses to produce current impulses, means to suppress certain of said current impulses, means responsive to phase differences between said signal impulses and the 40 movements of the distributor to control the synchronization of the distributing device with the transmitting device.

2. A system of the type described comprising means to generate and transmit signal 45 impulses at intervals, and of duration, which are integral multiples of the period of the elemental impulses, a receiving station having a distributing device for said signal impulses and electric motive means to 50 drive said distributing device, with means responsive to the said signal impulses to produce current impulses, means to suppress certain of said current impulses, means responsive to phase differences between said 55 signal impulses and the movements of the distributor to control and vary the magnetic excitation of said electric motive means and thus control the speed of the distributing device to synchronize it with the sending 60 transmitter.

3. A system of the type described comprising means to generate and transmit signal 65 impulses at intervals, and of duration, which are integral multiples of the period of the elemental impulses, a receiving sta-

tion having a distributing device for said signal impulses and an electric motor to drive said distributing device, with means responsive to the said signal impulses to produce current impulses, means to suppress certain of said current impulses, means responsive to phase differences between said signal impulses and the movements of the distributor to vary the field excitation of the electric motor driving the distributor. 70

4. In a system of the type described, a sending station having means to produce signal impulses at intervals, and of duration, which are integral multiples of an elemental period, a receiving station including 80 a rotary distributor for said signal impulses, a motor to drive said distributor, means to determine the speed of the motor by the phase relation existing between the signal impulses and the movements of the rotary distributor, and operating to bring the motor and distributor into exact synchronism 85 with the means to produce signals at the sending station.

5. In a system of the type described, 90 means to supply signal impulses at intervals, and of duration, which are integral multiples of an elemental period, a rotary distributor to apportion said signal impulses among a plurality of receiving circuits, a 95 motor to drive said distributor, means responsive to current changes in said signal impulses whereby other current impulses are generated and their positive and negative half waves are delivered to the field winding of the said motor, and means responsive to the various phase relation of the signal impulses and the rotary distributor to vary the amplitude of a group of said 100 current impulses. 105

6. In a system of the type described, 110 means to supply signal impulses at intervals, and of duration, which are integral multiples of an elemental period, a rotary distributor to apportion said signal impulses among a plurality of receiving circuits, a motor to drive said distributor, means responsive to current changes in said signal impulses whereby other current impulses are generated and their positive and negative half waves are delivered to the field winding of the said motor, and means responsive to the various phase relation of the signal impulses and the rotary distributor to vary the field excitation of said motor. 115

7. In a system of the type described, 120 means to emit signal impulses at intervals, and of duration, which are integral multiples of an elemental period, a distributor substantially synchronized with said signal 125 impulses and adapted to apportion the same among a plurality of circuits, means responsive to current changes of said signal impulses to produce by and from said signal impulses current impulses, a thermionic 130

valve to suppress said current impulses moving in one direction, and means to employ the current impulses moving in the other direction to effect exact synchronism of said distributor with said signal impulses.

8. A system of the class described comprising means to produce signal impulses at intervals, and of duration, which are integral multiples of an elemental period, means 10 to produce through said signal impulses synchronizing impulses at intervals, said synchronizing impulses being also integral multiples of the same elemental period, a distributor kept in synchronism through the 15 action of the signal impulses and the synchronizing impulses to distribute the signal impulses among a plurality of circuits, means responsive to the varying phase relation of the signal impulses and the synchronizing impulses to bring to and maintain at synchronism the movement of the distributor.
9. In a system of the type described, means 20 to emit signal impulses at intervals which are integral multiples of an elemental period, a distributor substantially synchronized with said signal impulses and adapted to apportion the same among a plurality of circuits, means to produce current impulses corresponding to both ends of each signal, means 25 to suppress such current impulses in one direction, a switch, control circuits, and means including said switch to distribute the remaining impulses to said control circuits, 30 and means actuated through said control cir-

cuits to establish the direction of the corrective synchronizing effort of said remaining impulses upon said distributor.

10. In a system according to claim 9, means to drive said switch from the distributor actuating device.

11. In a system according to claim 9, means controlled by said switch to govern the phase relation of the distributor to said signal impulses.

12. In a system according to claim 9, means controlled by said switch to control the speed of the distributor.

13. In a system according to claim 9, means responsive to the summation of all 50 phase corrections to control the speed of the distributor.

14. In apparatus for transmitting electrical signals which are produced at intervals, and of duration, that are integral multiples 55 of an elemental period, a sending apparatus for the signals at one station, a receiving apparatus for the signals at another station, a distributing device for the signals at the receiving station, means for actuating the receiving device, means responsive to the incoming signals for producing electrical impulses, means for causing the impulses so produced to be delivered as uni-directional impulses and means for utilizing such uni-directional impulses to synchronize the movements of the actuating means for the distributing device with the incoming signals.

FREDERICK EUGENE PERNOT.
